UNITED STATES PATENT OFFICE.

CHARLES E. BOWERS, OF WESTMINSTER, MARYLAND.

HEATING SYSTEM.

No. 822,819.

Specification of Letters Patent.

Patented June 5, 1906.

Application filed December 28, 1904. Serial No. 238,577.

To all whom it may concern:

Be it known that I, CHARLES E. BOWERS, a citizen of the United States, residing at Westminster, in the county of Carroll, State 5 of Maryland, have invented certain new and useful Improvements in Heating Systems; and I do hereby declare the following to be a full, clear, and exact description of the invention, such as will enable others skilled in the 10 art to which it appertains to make and use the same.

This invention relates to devices for use in poultry culture, and more particularly to heating systems therefor, and has for its object 15 to provide a heating system for this purpose which will be simple and efficient and which will be arranged to maintain the temperature of the device heated at a predetermined point.

20 Another object is to provide a heating system of the water-circulating type which will be provided with an overflow-tank for the reception of the excess of water caused by expansion and which will be arranged to return the water to the system after it has again contracted.

It will be understood that the device may be used in connection with incubators, brooders, or similar devices.

30 Other objects and advantages will be apparent from the following description, and it will be understood that modifications of the specific construction shown may be made and any suitable materials may be used for 35 the various parts without departing from the spirit of the invention.

In the drawings forming a portion of this specification, and in which like numerals of reference indicate similar parts in the several 40 views, Figure 1 is a front view of an incubator provided with the present invention. Fig. 2 is an end view of the structure shown in Fig. 1, showing the boiler attached thereto. Fig. 3 is a longitudinal section of the incubator, taken on line 3 3 of Fig. 2. Fig. 4 is a top plan view showing the top of the incubator broken away to expose the heating-pipes.

Referring now to the drawings, the present invention is shown applied to an incubator 5, including the usual hollow body portion and supporting-legs. Secured to one end of the incubator, exteriorly thereof, there is a boiler 6, having a plurality of longitudinally-extending fire-tubes 7 passing therethrough 55 and provided with a lamp or other heating

device 8, disposed therebelow, there being a suitable conductor 9, provided for the passage of heat from the lamp to and through the tubes 7.

Engaged with the upper end of the boiler 60 there is a cap 10, having a struck-up portion centrally thereof, which forms a heat-dome 11, and extending laterally from the heat-dome there is a flue 12, which extends into the incubator through the wall thereof to a point at 65 approximately the central vertical axis of the body portion, where it is turned upwardly, as shown at 13, extending through the top of the body portion. Formed through the top of the heat-dome 11 there is a small opening 70 14, and pivoted upon the top of the body portion there is a damper-arm 15, which extends beyond the end of the body portion and from which there depends a damper 16, the damper-arm being movable to bring the 75 damper into and out of position to close the opening 14. A thermostat 17 is located within the body portion and is connected with the damper-arm 15 for movement thereof to bring the damper into position to close the 80 opening when the temperature within the body rises above a certain point, and the thermostat is arranged for adjustment in any suitable manner.

At the side of the boiler adjacent to the 85 end of the body portion it is provided with a laterally-projecting extension 18, which extends from the top to the bottom of the boiler, the extension being hollow and communicating with the interior of the boiler. 90 This extension lies within an opening 19 in the end of the body portion and projects into the latter. Disposed within the body portion are pipe-coils 20, lying adjacent to the walls thereof, the coils being formed from a 95 continuous pipe or a plurality of connected sections of pipe, and at one end this pipe communicates with the extension 18 of the boiler, adjacent to the upper end thereof, and at the remaining end with the extension adjacent to 100 the lower end thereof. The pipe-coils are so slanted that the heated water from the boiler will pass out through the pipe communicating with the upper end of the extension and through the coils of pipe back to the boiler at 105 the lower end of the extension, the expansion of the water causing the circulation of the water, as will be readily understood.

Extending outwardly from the boiler adjacent to its bottom there is a pipe 21, which is 110

turned upwardly, as shown at 22, and has mounted upon its upper end an overflow-tank 23, with which it communicates, this tank being located above the top of the boiler. Communicating with the boiler at its top and extending upwardly therefrom there is an overflow-pipe 24, which is turned laterally, as shown at 25, to discharge into the tank 23, and it will be apparent that any excess of water caused by expansion will pass out through the pipe 24 to the tank 23, where it will be cooled and from which it will be returned by the pipe 21 to the boiler. The tank 23 is open at its top, so that the boiler 15 may be filled by pouring water into the tank.

The incubator is provided with an air-ingress pipe 26 and an air-egress pipe 27, communicating with the interior of the incubator adjacent to the top and bottom thereof, respectively, for ventilation thereof. Externally of the incubator the ingress-pipe is turned downwardly, while the egress-pipe is turned upwardly, the former being considerably larger than the other, as shown.

What is claimed is—

In an incubator, the combination with a hollow body portion, of a boiler located exteriorly thereof and having a lateral projection extending into the body portion, pipe-coils lying within the body portion and communicating with the projection at the upper and at the lower portions thereof, a flue in the boiler, a pipe passed through the body portion and communicating with the flue, means for heating the boiler, an overflow-tank disposed above the boiler, a pipe communicating with the lower portion of the tank and with the lower portion of the boiler, and a second pipe communicating with the upper portion of the tank and with the upper portion of the boiler.

In testimony whereof I affix my signature in presence of two witnesses.

CHARLES E. BOWERS.
